UNITED STATES PATENT OFFICE.

CLARENCE O. HOFFMAN, OF DETROIT, MICHIGAN, ASSIGNOR OF ONE-HALF TO LOUIS SCHULMAN, OF DETROIT, MICHIGAN.

WINDOW-CLEANING DEVICE.

Application filed December 1, 1921. Serial No. 519,061.

To all whom it may concern:

Be it known that I, CLARENCE O. HOFFMAN, a citizen of the United States of America, residing at Detroit, in the county of Wayne and State of Michigan, have invented certain new and useful Improvements in Window-Cleaning Devices, of which the following is a specification, reference being had therein to the accompanying drawings.

10 This invention relates to a window cleaning device and has special reference to the windows of street cars, locomotive cabs, automobile bodies, and any window which is exposed to the elements and liable to be 15 befogged or rendered non-transparent by the accumulation of snow, sleet, water or other matter.

The primary object of my invention is to provide a window sash with a rotary transparent pane or plate, a stationary wiper member in engagement with the pane of glass, and suitable connections with a source of power for rotating the rotary pane or plate, so that the wiper member will remove 25 matter from the outer face of the pane or plate or at least clear a space for uninterrupted vision.

Another object of my invention is to furnish a window sash with glass cleaning means that may be operated, at will, by a person adjacent the window sash, and when such window sash forms part of a vehicle the source of power utilized to drive the vehicle may also be used for operating the 35 window cleaning device.

A further object of my invention is to provide a window sash construction that may be advantageously used in connection with street cars, particularly the end windows thereof, the sash construction including a pane wiping device which obviates the necessity of a motorman repeatedly wiping off a pane of glass in order to see through the same, as now practiced when the motorman's visibility is interfered with by rain and snow.

The above are a few of the objects which may be attained by a construction which will be hereinafter described and then claimed, 50 and reference will now be had to the drawing, wherein—

Figure 1 is a diagrammatic cross-sectional view of a street car showing the motorman's window in accordance with my invention;

Fig. 2 is an enlarged vertical sectional view of the window construction;

Fig. 3 is a view of the inner side of a window illustrating a slight modification of my invention, and

Fig. 4 is a cross sectional view of a portion of the same.

As showing one type of vehicle to which my invention may be applied, the reference numeral 1 denotes a street car body having a window frame 2 above a hollow end wall 3 in which may be housed a sash 4 slidably mounted in the window frame 2. The sash 4 is in the form of an opaque panel provided with a circular opening 5 and rotatable in said opening is a transparent disk 6 or circular pane or plate of glass 6 which is retained within the opening 5 by circular rings 7 on the inner and outer sides of the panel 4 about the opening 5. The pane of glass 6 cannot become accidentally displaced and the lower edge of said pane of glass may be supported on flanged anti-frictional rollers 8 set in cut away portions 9 of a panel 4, these rollers supporting the pane of glass so that it may be easily revolved between the rings 7 and in the opening of the panel 4. The panel is adapted to be held in a raised position in the frame 2 by a catch 10 or any other suitable sash holding device. By releasing the catch 10 the panel and its pane of glass may be lowered into the hollow wall 3, as indicated by dotted lines in Fig. 1.

Centrally or axially of the pane of glass 6 is a socket 11 in which is detachably mounted the end of a flexible shaft 12, said shaft extending downwardly through the floor 13 of the street car so that its lower end may be driven from an axle 14 of the street car or any suitable source of power. The power transmission mechanism by which the axle 14 may operate the shaft 12 includes a gear wheel 15 on the axle 14 meshing with a gear wheel 16 on a shaft 17, journaled in hangers 18, carried by the floor 13 of the car. Slidably keyed on the shaft 17 and adapted to rotate therewith is a clutch member 19 that may be shifted into engagement with a clutch member 20 loose on the shaft 17 but to which the end of the shaft 12 is connected, so that the shaft 12 may be driven from the shaft 17 when the clutch members are in engagement with

each other. Any suitable means may be employed for shifting the clutch member 19, preferably a bell crank 21 and a treadle 22, said treadle being located adjacent the controller 26 of the street car to permit of the motorman controlling the operation of the shaft 12 by foot pressure.

Attached to the front side of the panel 4, at the lower edge thereof, is an upstanding stationary wiper member 23 frictionally engaging the front or outer face of the pane of glass 6, said wiper member extending in proximity to the socket 12 and having a radial relation thereto. When the pane of glass 6 is rotated in its panel the outer or front face of the pane of glass will be wiped off by the wiper member 23 and it may be only necessary to revolve the pane of glass for a few seconds when it will be cleaned sufficiently to permit of the motorman or operator of the car making observations through the glass. It will not be necessary for the motorman to leave the car to clean the outer face of the window pane, nor even remove his hands from the usual controlling devices of the street car, it being only necessary to depress the treadle 22 when the pane of glass is to be revolved and cleaned. When the pane of glass is to be lowered by letting down the panel 4 into the hollow wall 3, the upper end of the shaft 12 may be removed from the socket 11.

Instead of driving the pane of glass 6 by a connection at its middle portion, I

may dispense with the socket 11 and use a shaft driven friction wheel 24. This friction wheel may be placed in a gap or opening 25 of the panel 4 to engage the lower edge of the pane of glass, as shown in Fig. 3, and with the pane of glass resting on this driven friction wheel and the rollers 8, said pane of glass can be easily revolved with the wiper member 23 against the front or outer face of the glass.

While in the drawings there are illustrated the preferred embodiments of my invention, it is to be understood that the structural elements are susceptible to such changes, in size, shape and manner of assemblage as fall within the scope of the appended claim.

What I claim is:—

The combination of a window frame, a movable sash therein adapted to be raised and lowered relative to said window frame, a pane of glass rotatably mounted in said sash, a wiper member carried by said sash and engaging said rotary pane of glass, and a driven flexible shaft adapted to have an end thereof inserted in said rotary pane of glass when said sash is in a raised position for rotating said pane of glass.

In testimony whereof I affix my signature in presence of two witnesses.

CLARENCE O. HOFFMAN.
